UNITED STATES PATENT OFFICE.

GEORGE A. COLLETT, OF MACON, MISSOURI, ASSIGNOR OF ONE-HALF TO CHARLES D. STAPLIN, OF MACON, MISSOURI.

SNAP-HOOK.

1,243,590.

Specification of Letters Patent. Patented Oct. 16, 1917.

Application filed December 6, 1916. Serial No. 135,446.

To all whom it may concern:

Be it known that I, GEORGE A. COLLETT, a citizen of the United States, residing at Macon, in the county of Macon and State 5 of Missouri, have invented certain new and useful Improvements in Snap-Hooks; and I do hereby declare the following to be a full, clear, and exact description of the invention, such as will enable others skilled 10 in the art to which it appertains to make and use the same.

This invention relates to improvements in snap hooks.

The object of this invention is the 15 vision of a snap hook which is especially adapted for establishing a connection between various articles such as chains, harness and the like, and is so constructed as to provide a snap hook that will effectively hold, and 20 thus obviate the pulling apart at its point of connection.

A still further object of this invention is to provide a snap hook of this character which is provided with a body and a pair of 25 independently rotatable disks for frictionally engaging a body and thus a chain or other articles may be connected to the body of the hook.

A still further object of this invention is to 30 provide a snap hook of this character which will be simple, practical, and comparatively inexpensive in construction and one that can be manufactured and sold at a low cost.

With these and other objects in view, the 35 invention consists in the novel combination and arrangement of parts hereinafter more fully described and set forth in the claims hereto appended.

In the drawings:

40 Figure 1 is a top plan view of my snap hook made in accordance with the invention,

Fig. 2 is a longitudinal sectional view of the same,

45 Fig. 3 is another top plan view of the top disk removed.

Like numerals of reference designate corresponding parts in all the figures of the drawings.

50 Referring more particularly to the drawings, the numeral 1 designates an elongated body which is substantially oval in cross section and is constructed of suitable metal, or any other material suitable for the purpose.

55 The elongated body 1 is provided adjacent

one end with an opening centrally of its opposite side longitudinal edges, the purpose of which will be hereinafter more fully described.

The body 1 is provided intermediate its 60 ends on its opposite side faces thereof with circular recesses 3 which recesses are concentrically related and the partition wall 4 dividing the recesses is provided with a central opening 5 through which is adapted to 65 extend a pin 6.

The side walls 7 of the recesses 3 are adapted to engage the peripheral edge 8 of the concavo-convex disks 9 and 10. The disks 9 and 10 are concavo-convex in cross 70 section and have their concave faces innermost and are independently rotatable upon the opposite ends of the pin 6. The disks 9 and 10 are each rotatably mounted on pin 6 and have their peripheral edges engaging 75 the side wall 7 and partition walls 4 of the recesses 3 as clearly shown in Fig. 2 of the drawings. The engaging of the peripheral edge 8 with the side wall 7 and partition wall 4 serve to hold the disks against 80 accidental rotation, the purpose of which will be hereinafter more fully described.

The partition wall 4 is provided with a transversely extending opening 11 and has its outer end opening out through the side 85 edge of the body 1, and the transversely extending opening 11 has its inner end communicating with the longitudinally extending opening 12, which opening communicates with the transversely extending opening 13 which terminates into a longitudinally extending opening 14 in the body 1, the purpose of which will be hereinafter 90 more fully described.

Each of the disks 9 and 10 are provided 95 with elongated slots 15 which open out through the peripheral edge thereof and are adapted to aline with the openings 11, 12, 13 and 14 of the partition wall and body, thus permitting a link of a chain or other 100 connecting member to be securely fastened within the body.

The opening 12 is adapted to receive a flexible connection therein which permits the hook to be suspended from a device, and 105 prevented from being lost.

In operation:

The disks 9 and 10 have their elongated slots 15 alined with the slots 11 in the partition wall 4 of the body 1. A link or other 110

connecting member is slipped into the alined slots of the disks and partition wall toward the rear wall 16. The disks are then forced around moving the links into the slots 12 and then into the slot 13 and into the longitudinal slot in the body 1, and the disks are moyed past the slots 14 in the body 1, and the link is held connected with body 1 and against movement by moving the disks 9 and 10 out of registration with the longitudinal openings 14.

It will be understood that to remove the link it is only necessary to aline the disks 9 and 10 with the slots 14, 13, 12 and 11 and the link can be readily removed. While the disks are away from an alinement with the slots 11, 12, 13, and 14, it can be readily understood that it will be impossible for the link to be accidentally removed from the body 1.

The frictional engagement of the peripheral edge of the disks 9 and 10 with the wall 7 and partition wall will serve to hold the disks against accidental rotation.

25. What is claimed is:

1. A snap hook comprising a body having a longitudinally extending slot therein and adjacent one end arranged centrally of the side edges thereof, said body provided on its opposite side faces with circular recesses which intersect the inner ends of said slot, the recesses in the body defining a partition wall which is provided with a transversely

arranged slot which communicates the inner end with the longitudinal slot in the body, 35 and a disk rotatably mounted in each of the recesses and provided with transversely arranged slots which communicate with the slot in the partition wall and body to permit a fastening link to be secured in the 40 longitudinal slot of the body.

2. A snap hook comprising a body substantially oval in cross section, said body provided intermediate its end on its opposite side faces with circular recesses, forming annular shoulders, said recesses defining a partition wall which is provided centrally with an opening, a pin arranged through the opening and its ends projecting beyond the opposite side faces of the body, 45 a pair of disks concavo-convex in cross sections, each disk rotatably mounted on one end of the pin and having its peripheral edge abutting the annular shoulder formed by the side wall of the recesses, said body 50 and wall provided with slots and said disk provided with slots in alinement with the slots in the body wall to permit a link to be fastened within the slot in the body, as and for the purpose specified.

In testimony whereof I affix my signature in presence of two witnesses.

GEORGE A. COLLETT.
